UNITED STATES PATENT OFFICE

HOWARD B. LAMBDEN, OF BALTIMORE, MARYLAND, ASSIGNOR OF ONE-HALF TO
JAMES R. BRINKLEY, OF BALTIMORE, MARYLAND

BUOY-LAUNCHING DEVICE

Application filed June 5, 1929. Serial No. 368,577.

The present invention is directed to improvements in devices for launching buoys.

The primary object of the invention is to provide a device of this character so constructed that one or more buoys may be quickly released and precipitated into the water in order that a person overboard may grasp the same, means being provided to retrieve the buoys.

10 Another object of the invention is to provide a device of this character so constructed that a proper officer can control the release thereof from a remote point, as for instance, from the bridge of a vessel.

15 Another object of the invention is to provide a device of this character constructed in such manner that a person standing near the device can actuate the same to release the buoys independently of the remote control means.

20 Another object of the invention is to provide a device of this character which includes a casing adapted to be secured to the rail of a ship at an inclined position in order that when the buoy is released it will clear the side of the vessel.

25 Still another object of the invention is to provide a device of this kind wherein an alarm will be sounded simultaneously with the release of the buoy, in order that members of the crew will be notified as to which buoy has been released so that they may stand by to actuate the reel for retrieving the buoy.

30 With these and other objects in view, this invention resides in the novel features of construction, formation, combination and arrangement of parts to be hereinafter more fully described, claimed and illustrated in the accompanying drawings, in which:

35 Figure 1 is a plan view of a vessel showing the arrangement of the buoy containing casings.

40 Figure 2 is a view of the casing with the front wall thereof removed.

Figure 3 is a vertical transverse sectional view through the device.

Figure 4 is a sectional view on the line 4-4 of Figure 3.

Figure 5 is a sectional view through one of the bearings.

Figure 6 is a diagrammatic view of the electrical circuit.

Referring to the drawings, the numeral 1 designates a casing, formed of suitable gauge sheet metal, said casing having diametrically opposed bearings 2 formed in its front and rear walls 3 and 4. Roller bearing assemblies 5 are mounted in these bearings for supporting the ends of the shaft 6 to which a reel 7 is fixed, said reel having wound thereon a line 8. This line is secured to the buoy 9 normally contained within the casing 1. The line is of a length to permit the buoy to float a considerable distance from the vessel after the buoy is released from the casing and cast overboard.

45 The inner end of the shaft 6 is provided with a square portion 10 to be engaged by the crank 11 to rewind the line upon the reel in order that the buoy can be returned to the casing after use.

The crank 11 is retained upon the inner wall 4 of the casing by clips 12 and 13 and is readily removable for engagement with the square portion 10 of the shaft to rewind the line upon the reel.

50 The back 4 of the casing has fixed thereto loops 14 for pivotally engaging the rail 15 of the ship, there being arms 16 connected to the sides 17 of the casing, said arms having their inner ends provided with forks 18 for detachably engaging a sub-adjacent rail 15. The arms 16 are of such length that when the forks are engaged with the rail the casing 1 will be disposed in inclined relation with respect to the ship's rail so that when the buoy is released it will clear the side of the vessel. Pins 19 are carried by the forks and serve 55 to hold the same against accidental disengagement.

gagement from the rail. The forks are disengaged from the rail when the vessel is docking in order that the casing can swing to a vertical position, thus preventing the same from contacting with any obstructions which might be present upon the dock. It will, of course, be understood that as soon as the vessel has left the dock, the casings are fixed in their inclined operative positions.

10 A trap door 20 is hingedly connected to the lower edge of the front wall 3, as at 21, therebeing a coil spring associated with the hinged connection and arranged to swing the door 20 when released, to the position, as shown in dotted lines in Figure 3. The door has fixed to its free edge a lug 22, the purpose of which will appear later.

15 A solenoid 23 is secured to the outer surface of the wall 4 by a band 24, the armature 25 thereof having a link 26 pivotally connected thereto, said link being pivotally connected to the post 27. A latch bar 28 is pivotally connected intermediate its ends to the casing wall, as at 29, and its upper end carries 20 the post 27 which is pivotally connected to the link 26, there being a hook 30 at the lower end of said bar for normally engaging the lug 22 to retain the trap door 20 in closed 25 position to sustain the buoy 9.

20 The armature has one arm extending through a supplemental casing or housing 31 which is secured to the main casing wall, as shown to protect the solenoid and to this extended end is secured a chain 32 to permit of 25 manual operation of the armature when necessary.

25 Conductors 33 and 34 are connected to the solenoid, the conductor 34 leading to the bell 35, and leading from the bell to the switch 36 30 is a conductor 37. The switch obviously serves to close the circuit when engaged with the terminal of the conductor 38. Current is furnished to the solenoid and bell from the ship's electrical plant. Obviously, when the 35 switch is closed the solenoid will be energized, thus throwing the armature 24 inwardly, whereupon the latch bar 28 is swung so that the hook 30 thereof will disengage the lug 22, thus releasing the trap door 20 to 40 permit the buoy 9 to slide from the casing 1. The bell 35 will sound when the circuit is closed and the solenoid energized, and in this manner the crew will be cognizant of which buoy has been released in order to stand by 45 and rewind the line upon the reel to retrieve the buoy in order that the person clinging thereto can be returned to the ship in safety. The switches 36 controlling release of the 50 buoys are located on the bridge of the vessel so that an officer can, upon being notified that a person is overboard, close the circuit to release one or more of the buoys. Obviously, the buoy released will be one that will reach the person overboard in the quickest time.

55 Should a person fall overboard and be ob-

served by a member of the crew or other person, the armature 25 may be manually operated by pulling upon the chain 32, thereby releasing the buoy without the necessity of notifying an officer upon the bridge.

60 Rollers 33' are journaled transversely of the casing 1 to relieve friction when the line is being unwound or rewound upon the reel and to also prevent wear thereof.

65 As shown in Figure 1, eight casings are illustrated, arranged in groups of two upon each side of the vessel, but it will, of course, be understood that the invention is not limited to any specific arrangement and number of launching devices used.

70 The reel is protected by a hood 34' suitably fixed to the top of the casing 1.

75 From the foregoing, it is thought that the operation, and many advantages of the herein described invention will be apparent to those skilled in the art without further description, and it will be understood that various changes in the size, shape, proportion and minor details of construction may be resorted to without departing from the spirit 80 or sacrificing any of the advantages of the invention.

85 What is claimed is:

1. A buoy launching device comprising a 90 casing, a reel mounted in the casing, a line windable upon the reel, a door closing the lower end of the casing, a buoy mounted in the casing and sustained by the door, and combined means manually and electrically actuated to release the door to discharge the 95 buoy from the casing, the buoy being retrievable after release by winding the line upon the reel.

2. A buoy launching device comprising a 100 casing having a reel mounted therein, a line windable upon the reel, a spring actuated trap door closing the lower end of the casing, a buoy mounted in the casing and resting upon the door and connected with said line, a 105 latch bar carried by the casing for holding the door closed, a solenoid carried by the casing and having its armature connected with the latch bar, and means remote from the casing for energizing the solenoid to actuate the latch to permit release of the door and 110 the discharge of the buoy from the casing.

3. A buoy launching device comprising a 115 casing, a reel mounted therein, a door closing the lower end of the casing, a buoy normally supported upon the door, a line windable on the reel and connected with the buoy, a latch bar mounted on the casing for normally holding the door closed, a solenoid having its armature connected with the latch for actuating the same to release the door when the solenoid is energized to permit release of the buoy from the casing, and an audible signal adapted to be sounded when the solenoid is energized.

4. A buoy launching device comprising a 120

5 casing, a buoy mounted in the casing, means for releasing the buoy from the casing, means for pivotally connecting the casing to the side rail of a vessel, arms pivotally connected with the casing for engagement with a rail to hold the casing in an inclined position, said arms being releasable from the rail to permit the casing to assume a vertical position.

10 In testimony whereof I affix my signature.
